COMBINATION MERCHANTISE SHIPPING
PACKAGE AND DISPLAY DEVICEFrederick George Fisher, Waban, Mass., assignor
to National Folding Box Company, New Haven,
Conn., a corporation of New Jersey

Application August 25, 1933, Serial No. 686,669

4 Claims. (Cl. 206—78)

This invention relates to a combination merchandise shipping package and display device and more particularly to a display structure upon which the merchandise may be positioned during shipment and when removed from the outer container may be set up to provide an attractive display for the merchandise.

The merchandise shipping package and display device forming the subject matter of this invention comprises generally a rack member formed from a single blank of relatively stiff paperboard material. A plurality of pockets are suspended from and detachably connected to the front face of the rack member. Each pocket member may be formed from a single blank of paperboard material comprising a front wall, rear wall, side walls and a supporting bottom wall. The merchandise to be displayed is inserted into the pockets and suitably arranged in an attractive manner therein. Each pocket is provided with a pair of hook portions which may be inserted through spaced slots provided in the rack member. The hook portions are provided with hooks at the ends thereof which may be detachably connected together on the rear face of the card. A collapsible easel attached to the rear face of the rack member is also preferably provided. The easel comprises a pair of collapsible wings which may be folded flat against the rack member during shipment. The wings may be expanded outwardly and held in set up condition by a slotted tube portion operative to detachably interlock with the wings when folded in set up position.

The merchandise is arranged within the pockets by the merchandise manufacturer and in this manner the manufacturer is assured that his merchandise will be displayed in the most effective manner by the storekeeper. A large variety of different objects may be effectively displayed in this manner. Elongated articles, such as pencils, crayons, pens, toothbrushes, toilet articles and dispensing tubes are especially adapted for shipment and display in my combination shipping package and display device. Guard members, comprising a single strip of paperboard material arranged around the merchandise, may be provided to insure additional protection to the merchandise when the rack member upon which the merchandise is mounted is inserted into the outer container. The outer container may comprise any form of suitable box or carton of such size as to snugly receive the rack member and associated pockets loaded with merchandise. The guards may be of sufficient depth to provide ad-

ditional reinforcement to the container during shipment.

An object of this invention is to provide a combination merchandise package and shipping device which may be shipped to the merchandise manufacturer in collapsed condition, which may be easily and quickly filled with merchandise arranged in an attractive manner, and which may be removed from the outer container and set up by the storekeeper so as to provide an attractive and pleasing display for the merchandise.

Another object of this invention is to provide a display device formed from single blanks of paperboard material which can be made entirely by automatic machinery, which may be stored in collapsed condition so as to occupy a minimum of space, and which may be easily and quickly assembled by the manufacturer to receive the merchandise without the use of machinery or tools.

Another object of this invention is to provide a display device comprising a rack member having merchandise receiving pockets attractively arranged and detachably connected thereto.

Still another object of this invention is to provide a display device comprising a rack member, merchandise receiving pockets and a collapsible supporting easel, all of which may be formed from paperboard material by machine operation, which is furthermore economical to manufacture, which is flexible and is adapted for the display of many different kinds of merchandise, which occupies a minimum of space, which may be easily and quickly set up by the storekeeper, and from which the merchandise may be conveniently dispensed when sold.

Other objects of this invention will become apparent as the disclosure proceeds.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which

Fig. 1 is a face view of a paperboard blank which comprises the rack member of the display device;

Fig. 2 is a face view of the supporting easel in expanded position ready to be attached to the rack member;

Fig. 3 is a blank from which the merchandise receiving pocket is made;

Fig. 4 is a perspective view of the assembled display device having merchandise supported in certain of the pockets thereof;

Fig. 5 is a perspective view of the outer container within which the rack member loaded with merchandise is inserted and supported during shipment;

Fig. 6 is an enlarged vertical cross sectional view through the outer container showing the display device loaded with merchandise packed therein;

Fig. 7 is an enlarged perspective view of an article of merchandise surrounded by the guard member used to protect the merchandise during shipment and storage;

Fig. 8 is an interior perspective view of the pocket forming blank shown in Fig. 3 in the process of folding and assembly;

Fig. 9 is a perspective view of the completed pocket formed from the blanks shown in Figs. 3 and 8; and

Fig. 10 is a rear perspective view of the display device showing particularly the means for detachably securing the pockets to the rack member and the construction of the collapsible easel.

Similar reference characters refer to similar parts throughout the several views of the drawings and specification.

There is shown in Fig. 1 the rack member A which is formed from a single blank of relatively stiff paperboard material. The blank may be formed into a number of attractive shapes and may be decorated on the front face thereof to provide an attractive background for the merchandise mounted thereon.

The merchandise is arranged in suitable pockets formed from the blank C shown in Fig. 3. Each pocket comprises a rear wall 1, a front wall 2 and side walls 3 defined by score lines 5. The blank C is bent into tubular form and held in this position by a securing tab 4 glued or otherwise secured to the side wall 3. A bottom wall 6 hinged to the front wall 2 along the score line 8 is provided with a flap 7 which is inserted into the pocket to rest along the rear wall 1. Bottom tabs 9 extend inwardly from each of the side walls 3 and complete the bottom structure. It is seen that a pocket member comprising rear wall 1, front wall 2, side walls 3, bottom wall 6, and an open top is thus provided.

Any desired number of pockets may be attractively arranged on the front face of the rack member. For the purpose of illustration, there is shown in Fig. 4 pockets C mounted on the rack member A. The pockets are secured in position by means of hook portions 11 and 12 which extend from the opposite ends of the rear wall 1 of the pocket forming blank C. Spaced slots are provided in the rack member A to receive the hook portions 11 and 12, the hook portion 11 being inserted into the slot 21 and the hook portion 12 into the slot 22. The hooked ends 13 and 14 of the hook portions 11 and 12 respectively are connected together on the rear face of the rack member in the manner shown more particularly in Fig. 10.

To maintain the rack member A, with the pockets C mounted thereon, in set up display condition, a collapsible easel formed from a blank B, shown more particularly in Fig. 2, is provided. The easel comprises a wall portion 32 which is glued or otherwise secured to the rear face of the rack member A. Side wings 31 hinged to the rear wall 32 normally lay flat against the rear face of the rack member when in collapsed con-

dition. The wings 31, however, are adapted to be bent at right angles to the rear wall 32 so as to provide brace supports for the rack member when in display position, as shown more particularly in Fig. 10. The wing portions 31 are held in display position by means of a lock portion 34 which is cut out from the blank B along the cutout lines 35, 36, and 40, as shown in Fig. 2. The lock portion 34 is adapted to hinge outwardly along the score line 37 and is provided with a pair of cuts or slots 38 which are adapted to receive the inside edge 40 of the wing member 31 to maintain the wings in fixed set up position. The bottom edge 39 of the wing portions 31 may be cut at an angle so as to support the rack member A in a slightly inclined position, as shown in Fig. 10. The easel B is thus formed from a single blank of paperboard material by a simple cutting and scoring operation.

The rack member A is preferably formed of relatively stiff paperboard material which will carry considerable weight without buckling. The blank A is also formed by means of a simple cutting operation. The pocket members C are also formed complete by a single cutting and scoring operation performed by automatic machinery. The entire assembly can thus be economically made entirely by machine operation.

The display device may be shipped and stored by the merchandise manufacturer in complete collapsed condition. The easel B is collapsed against the rear wall of the rack member A and the pockets C shipped and stored in the form of a collapsed tube, either attached to or free from the rack member A as desired. The merchandise manufacturer sets up the pockets by the simple operation of closing the bottom wall 6 which comprises turning the side wall tabs inwardly and inserting the bottom wall flap 7 into the tubular pocket. The merchandise is then arranged in an attractive manner within the pockets. An opening 10 may be provided in the front wall 2 of the pocket if desired to provide a decorative effect and in addition to provide a more complete view of the merchandise M positioned therein.

When the pockets C supported on the rack member A have been fully loaded with merchandise, a guard member E formed from a continuous strip of relatively stiff paperboard material comprising end walls 42 and 43, and side walls 41 is so shaped as to snugly fit around each pocket and the merchandise positioned therein. The end wall 43 of the guard may be glued or otherwise secured to the top portion 44 to form a continuous member, if desired. The display device having the guard members E positioned thereon is then inserted into an outer container D into which it snugly fits. The outer container D may be closed by a suitable top wall 51, inturned tabs 52 and an inturned flap 53. The guard member E is of sufficient depth to substantially span the space between the rack member A and the side wall of the outer container. The guard member E thus serves the additional purpose of bracing and reinforcing the outer container against inward collapse during shipment and storage. The guard E also performs the important function of retaining the merchandise locked against removal within the pocket during shipment and storage of the package.

Merchandise may be shipped and stored in the outer container D which fully protects the contents at all times. When the storekeeper desires the merchandise for display or sale, the rack

member A carrying the pockets C loaded with merchandise is removed from the outer container D and the guard members E lifted off. The easel B is then set up by swinging the wing portion 31 at substantially right angles to the rear wall portion 32. The locking portion 34 is then swung into horizontal position into locking engagement with the wing portions 31. The display device is thus completely set up and no adjustment or arrangement of the merchandise supported thereon is required. In this manner the merchandise manufacturer is assured that his merchandise will be displayed in the most attractive manner by the storekeeper and will be suitably advertised by the printed matter carried on the front face of the rack member A and associated pockets C. The combination shipping package and display device is adapted for use in connection with a large variety of merchandizable articles. It is especially adapted to receive and display elongated articles in packages such as toothbrushes, toilet articles, pencils, crayons, pens, dispensing tubes, tools, hardware supplies and household fixtures of various kinds. The whole may be economically made entirely by machine operation and provides a convenient and attractive means for merchandising the articles displayed. The guard E insures retention of the merchandise in the pocket during shipment and storage. The pocket as well as the goods is firmly retained in position during shipment and storage. Further the pocket and its contents cannot be easily pilfered or removed from the rack.

While certain novel features of the invention have been disclosed and are pointed out in the annexed claims, it will be understood that various omissions, substitutions and changes may be made by those skilled in the art without departing from the spirit of the invention.

40 What is claimed, is:

1. A merchandise display device including in combination, a rack member formed from a relatively stiff blank of paperboard material, a plu-

rality of merchandise receiving pockets, each pocket comprising a front wall, a rear wall, side walls and supporting bottom wall formed from a single blank of paperboard material, a pair of hook members extending from each of said pockets, and a plurality of paired slots in said rack member, each pair of slots adapted to receive a pair of hook members, the end of said paired hook members being detachably connected together to support the pocket in display position on the rack member, and a collapsible easel operative to support said rack member in display position. 5

2. A merchandise display device including in combination, a rack member formed from a single blank of relatively stiff paperboard material, a 15 merchandise receiving pocket comprising a front wall, a rear wall, side walls and a bottom wall, hook portions extending from the pocket to the rack member, and a collapsible easel constituting means to support said rack member in display 20 position.

3. A merchandise display device including in combination, a rack member formed from a single blank of paperboard material, a merchandise receiving pocket comprising a front wall, a rear 25 wall, and side walls, hook members integral with and extending from certain of said walls and extending through slots in the face of the rack member and detachably interlocked on the back thereof to support the pocket in display position 30 thereon.

4. A merchandise display device including in combination, a rack member formed from a single blank of paperboard material, a merchandise receiving pocket comprising a front wall, a rear 35 wall, side walls and a bottom wall, hook portions extending from the pocket for detachably connecting the pocket to the rack member, and a collapsible easel detachably secured to the rack member operative to support said rack member 40 in display position.

FREDERICK GEORGE FISHER.
